(57) **CLAIM**

The ornamental design for a rolling wheel game, as shown and described.

DESCRIPTION

FIG. 1 is a front, top perspective view of a rolling wheel game, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 2; and,

FIG. 11 is another perspective view thereof, shown in a position of use with an exemplary wheel.

The dash dot dash lines in FIGS. 1, 2, 9 and 10 are for the purpose of illustrating the enlarged view indicators and form no part of the claimed design. The evenly dashed lines are shown for the purpose of illustrating both parts of the rolling wheel game as well as environmental subject matter of the exemplary wheel. None of the dashed lines form part of the claimed design.
